UNITED STATES PATENT OFFICE

SAMUEL S. BAKER, OF WEBSTER GROVES, MISSOURI

HEAT REGULATOR FOR GAS STOVES

Application filed August 21, 1931. Serial No. 558,432.

My invention relates to improvements in gas stoves and particularly to automatic oven heat regulators therefor and their relation to other parts of the stove structure.

5 In present day gas stoves or ranges, commercially known as the table top or console type, the open burners are arranged to lie in substantially the same horizontal plane as the top part of the adjacent oven and the entire 10 top of the stove is capable of being enclosed by a suitable ornamental cover when the stove is not in use. In gas stoves of this type, it has been the custom to place the thermostatically controlled valve for regulating the 15 heat of the oven at the oven end of the stove in alignment with the thermostat in the oven, due to the fact that the hot top portion completely covers the side of the oven adjacent thereto. This type of installation has the 20 disadvantage that the regulator valve is remote from the valve controls for the open burners which prevents easy accessibility, especially, when the thermostat therefor is located near the rear of the oven, as is desirable 25 from the standpoint of maximum oven space.

Another disadvantage of this type of installation is the large amount of piping necessary to supply fuel to the oven burner by way of 30 the regulator valve. It is, therefore, one of the objects of my invention to provide, in a gas stove of the type referred to, a regulator valve for automatically controlling the oven burner supply, which is located adjacent the 35 control valves for the other burners and is regulated by the thermostat within the rear of the oven.

Another object of my invention is to provide connecting means between the regulator 40 valve and the thermostat which will permit the latter to accurately control the valve in accordance with the oven temperature regardless of the heat to which the connecting means may be subjected.

45 Still another object of my invention is to provide on a table top or console type gas stove, a regulator valve that is easily accessible, neat in appearance, and requires a minimum amount of fuel supply piping.

50 Other objects will become apparent from

the following description taken in connection with the drawings showing a preferred embodiment of my invention.

In the drawings Figure 1 is a front view of a table top type of gas stove disclosing my 55 invention in relation to the open burners and the oven; Figure 2 is a top view of Figure 1 with the cover removed and the oven in cross section; Figure 3 is a top view, partly in section, of the connection between the regulator 60 valve and the thermostat; and Figure 4 is a side view, partly in section, of the regulator valve and part of the connection with the thermostat.

In the embodiment of my invention illustrated by Figures 1 to 4 of the drawings, 1 indicates a gas stove of the table top type which is composed of an oven having a broiler section 2 and a top section 3, and an open 70 burner section 4 lying in the same plane as the top of the top section. A fuel supply pipe 5 extends into the side of the open burner section and is connected to the manifold 6 at the front thereof. The exposed burners 7 are connected to the manifold through suitable valves 8 in a well known manner. A fuel supply pipe 9 is connected through a manual valve 10, with the regulating valve 11 arranged at the front of the open burner section, which latter valve automatically controls the flow of gas to the oven burner 12 connected to the regulating valve by pipe 13. Situated in the rear of the oven section 3 near the top thereof is a thermostat 14 held in place by a suitable clip and extending through the oven walls 15 and 16 into the rear part of the open burner section 4 and connected to control the valve 11 by suitable mechanism broadly indicated by the numeral 17 and to be later referred to in detail.

It is thus seen that by this arrangement of the regulator valve and thermostat that a minimum amount of fuel pipe is used to connect the regulator valve and the oven burner with the manifold. It is also to be noted that the arrangement places the regulator valve adjacent the valves controlling the exposed burners, which is very desirable from the standpoint of accessibility. Also, by placing the thermostat in the top rear portion of the

oven section 3, it is free from being constantly hit and battered by the insertion of cooking utensils into the oven.

If in some of the table top or console type stoves there is sufficient space between the oven and the adjacent exposed burners 7, the regulator valve may be placed near the manifold adjacent the side of the oven.

Referring to Figures 3 and 4, the regulating valve, the thermostat, and the connections therebetween will be described in detail. The regulating valve 11 is composed of a casing 18 provided with an inlet chamber 19 and an outlet chamber 20.

The inlet chamber is in communication with the supply pipe 9 from the manifold by means of a fitting 21 attached to the valve casing. This fitting also connects the outlet chamber 20 to the pipe 13 leading to the burners. The usual adjustable by-pass 22 in the fitting supplies a minimum amount of gas from the pipe 9 to the pipe 13 to assure a supply of gas to the burner 12 if the valve is closed. A disc valve 23 is enclosed in the casing 18 and is provided with a seat 24, between the inlet and outlet chambers, for regulating the flow of gas therebetween. A valve stem 25 is screw-threaded within the central portion of the valve and the valve is provided at its outer surface with an integral rectangular portion 26.

A casing cap 27 is threadedly secured to the valve casing 18 and has a central opening 28 therethrough in alignment with the valve stem in which is rotatably mounted a setting member 29 provided with a recess 30 adapted to receive the integral portion 26 of the valve. A suitable valve spring 31 is interposed between the setting member and the valve 23 normally tending to maintain the valve on its seat. A knob 32 is connected to the outside of the setting member by means of a set screw 32', thereby providing a convenient means for adjusting the valve stem. Fixed to the valve casing is a second cap member 33 spaced from the cap 27 and provided with an arcuate opening 34 and appropriate indicia adjacent thereto. An indicating member 35 lies between the two cap members 27 and 33 and is rotatably secured to the setting member 29. Part of the surface of the indicating member adjacent the scale opening 34 is provided with an arcuate colored portion 35' to simulate a thermometer, one end of which cooperates with the indicia adjacent the opening 34 to indicate the setting of the member 29.

The valve casing 18 adjacent the inner end of the valve stem has an opening 36 therein into which is screwed a tube 37 extending across the section 4 between the exposed burners 7. A nut 38 securely locks the tube to the casing. The end of the tube adjacent the back of the section 4 is flared and secured to an L-shaped casing 39 by means of a nut 40.

The thermostatic expansion and contrac-

tion tube 41 is of the well known type and extends to the outside of the oven and is secured at its outer end to the L-shaped casing and is closed at its inner end by means of a screw cap 42 held in place by the lock nut 43. Enclosed within the part of the tube lying inside of the oven is a carbon rod 44 abutting at one end against the screw cap 42, and having its other end in engagement with a rod 45 which in turn engages a short rod 46 extending into the central chamber 47 of the L-shaped casing.

A T-shaped lever 48 is pivoted at its base within the chamber 47 and has one of its arms in engagement with the adjacent end of short rod 46 and its other arm in engagement with the end of a short rod 49 slidably in the part of L-shaped casing to which the tube 37 is connected. Interposed between the short rod 49 and the valve stem and lying within the tube 37 is a rod 50 completing the connection between the thermostatic tube and the valve. An opening 51 in the L-shaped casing closed by a plug 52 provides for assembly of the rods and the T-lever and a bracket 53 secured to the back of the section 4 of the stove affords a convenient support for the L-shaped casing.

Since the spring 31 is normally tending to hold the valve 23 on its seat, the end of the carbon rod 44 will be held in engagement with the cap 42 of thermostatic tube 41 by means of the valve stem, the rod 50, short rod 49, T-lever 48, short rod 46, and rod 45, and

there will be no lost motion in the entire connection. When the oven is cold the thermostatic tube 41 will be contracted and the valve will be unseated to allow gas to flow to the burner 12, the maximum opening of the valve being determined by the adjustment, by means of the manual setting member, of the position of the valve on the valve stem. When the burner has been lighted and the oven is heated, the thermostatic tube 41 will be expanded, thereby increasing its length. The length of the carbon rod is little affected by the heat and, therefore, the carbon rod will be moved in the thermostatic tube by the action of the valve spring 31 acting through the valve stem, connecting rods and T-lever, thereby closing or tending to close the valve.

The entire mechanism is so adjusted before installation that when the temperature of the oven reaches the value for which the setting member has been manually adjusted, the expansion of the thermostatic tube will have permitted the valve to close to a sufficient extent to prevent further increase of temperature. Any drop in temperature in the oven will cause the thermostatic tube to contract and the valve to open wider by the action of the connections against the valve stem. It is, therefore, seen that by means of the thermostatically regulated valve, the fuel supplied to the burner is always such as to maintain the temperature of the oven at the value

indicated by the setting of the manual control member.

It is to be noted in this installation that the part of the thermostatic tube on the outside of the oven, the L-shaped casing, and the tube 37 and all elements contained therein, are exposed to the heat of the open burners in section 4 and provision must therefore be made to prevent this heat from interfering with the accuracy of regulation. I accomplish this by constructing the moving elements of the connecting means between the thermostat and valve of materials having the same coefficient of expansion as the parts which enclose them. Thus tube 37 and rod 50 are of the same material such as copper; casing 39 and the parts 46, 49 and 48 are the same material such as brass; and rod 45 is of the same material as the tube 41 of the thermostat.

Having fully described my invention, what I claim as new and desire to secure by Letters Patent of the United States is:

1. In a stove having an oven and open burners located laterally of the oven, a thermostat positioned at the rear of the oven, a valve casing positioned laterally of the front of the oven and provided with a valve controlling the fuel supply to the oven, and means connecting the thermostat to the valve, said means comprising a tube rigidly connected to the valve casing and a rod within the tube to transmit movement of the thermostat to the valve.

2. In a stove having an oven and open burners located laterally of the oven, a thermostat in the rear of the oven, a valve casing positioned laterally of the front of the oven and provided with a valve controlling the fuel supply to the oven, and means connecting the thermostat to the valve, said means comprising a tube rigidly connected to the valve casing and a rod within the tube to transmit movement of the thermostat to the valve, said tube being exposed to the heat of an open burner when the latter is in operation and being of material having the same coefficient of expansion as the rod.

3. In a stove having an oven and open burners located laterally of the oven, a thermostat positioned at the rear of the oven, a valve casing positioned laterally of the front of the oven and provided with a valve controlling the fuel supply to the oven and means connecting the thermostat to the valve, said means comprising a tube rigidly connected to the valve casing, a casing located adjacent the rear of the oven and connecting said tube to said thermostat, a rod in said tube connected to said valve, and means in said casing for transmitting movement of said thermostat to said rod.

4. In a stove having an oven and open burners located laterally of and substantially in the plane of the top of the interior of the

oven, a thermostat in the rear of the oven, a valve casing positioned laterally of the front of the oven and provided with a valve controlling the fuel supply to the oven, and means connecting the thermostat to the valve, 70 said means comprising a tube rigidly connected to the valve casing and a rod within the tube to transmit movement of the thermostat to the valve, said tube being exposed to the heat of an open burner when the latter is in operation and being of material having the same coefficient of expansion as the rod.

5. In a stove having an oven and open burners located laterally of the oven, a fuel manifold in front of the open burners, a 80 valve casing positioned adjacent the fuel manifold and provided with a valve controlling the fuel supply to the oven, a thermostat in the rear of the oven and means exterior of the oven for connecting the thermostat to the valve.

6. In a stove having an oven and open burners located laterally of the oven, a fuel manifold in front of the open burners, a valve casing positioned adjacent the fuel manifold 90 and provided with a valve controlling the fuel supply to the oven, a thermostat in the rear of the oven, and means connecting the thermostat to the valve, said means comprising a tube rigidly connected to the valve casing and a rod within the tube to transmit movement of the thermostat to the valve.

7. In a stove having an oven and open burners located in a section of the stove situated laterally of the oven, a manifold and 100 manual valves in front of the burners, said valves controlling the fuel supply from said manifold to the open burners, a valve casing positioned adjacent the manual valves and provided with a valve controlling the fuel 105 supply of the oven, a thermostat located in the rear of the oven and extending into the open burner section, and means for connecting the thermostat to the valve.

8. In a stove having an oven and a burner 110 therefor, a valve casing positioned at the front of the stove and provided with a valve controlling the fuel supply to the oven burner, a casing at the rear of the stove, a thermostat comprising a tube rigidly connected to said casing and extending into the oven and a rod in said tube having a different coefficient of expansion from said tube, a tube rigidly connected to the valve casing and to the casing at the rear of the stove, a rod in 115 said last named tube operatively connected to the valve and means in said casing for operatively connecting the rod in the thermostatic tube with the rod in the last named tube, the thermostatic tube and the tube connected to the valve casing being at an angle 120 to each other.

9. In apparatus of the class described, the combination with a gas stove, of an oven 125 therefor, open burners adjacent the oven and

lying in the same plane as the top portion of said oven, a fuel manifold adjacent the front of said open burners, a burner for the oven connected to the manifold, a valve at the front of said open burners for controlling the fuel supplied to the oven burner, a valve stem, a thermostat in the rear of the interior of the oven and extending at an angle to the axis on said valve stem, and means for transmitting movement of said thermostat to said valve stem to control the valve.

10. In apparatus of the class described, the combination with a gas stove, of an oven therefor, open burners adjacent the oven and lying in the same plane as the top of the oven, a burner for the oven, a valve at the front of the open burners for controlling the fuel to the oven burner, a valve casing, a thermostat in the rear of the interior of the oven, means exposed to the heat of the open burners for transmitting movement of said thermostat to said valve, said means comprising a tube secured to the valve and connected with the thermostat, a rod operatively engaging the valve, and means for transmitting motion from the thermostat to the rod, said rod and tube being composed of material having the same coefficient of expansion.

11. In a stove having an oven and open burners, a valve casing positioned at the front of the stove and provided with a valve controlling the fuel supply to the oven, a thermostat in the oven, and means connecting the thermostat to the valve, said means comprising a casing at the rear of the stove, a tube rigidly connected to the valve casing and to the casing at the rear of the stove and a rod within the tube to transmit movement of the thermostat to the valve, said tube being exposed to the heat of an open burner and being of material having the same coefficient of expansion as the rod.

12. In testimony whereof, I hereunto affix my signature, this 19th day of August, 1931.
SAMUEL S. BAKER.
